MATTRESS TURNER

Moses Joseph Mandelbaum, New York, N. Y.

Application September 28, 1946, Serial No. 700,113

6 Claims. (CL 5—323)

1

This invention relates to beds.

A principal object of this invention is to provide a device to facilitate the reversal from side to side or from end to end of a mattress of an ordinary well-known bed.

Other objects and advantages will appear as the description of the particular physical embodiment selected to illustrate the invention progresses and the novel features will be particularly pointed out in the appended claims.

In describing the invention in detail and the particular physical embodiment selected to illustrate the invention, reference will be had to the accompanying drawing and the several views thereon, in which like characters of reference designate like parts throughout the several views, and in which:

Fig. 1 is a perspective view of a bed with my invention applied to the mattress and spring thereof; Fig. 2 is a cross sectional view on the plane indicated by the line II—II of Fig. 1, viewed in the direction of the arrows at the ends of the line and with certain parts shown in an operated position; Fig. 3 is a fragmentary cross sectional view on the plane indicated by the line III—III of Fig. 1, viewed in the direction of the arrows at the ends of the line; Fig. 4 is a perspective view illustrating the position of the parts of my invention when a mattress is being turned end for end; Fig. 5 is a side elevational view of a mattress pivot pin used in my invention; Fig. 6 is a fragmentary side elevational view showing a mattress band and a special bore therethrough used in my invention; Fig. 7 is a perspective view of a pivot supporting mattress clasp used in my invention.

1 designates an ordinary bedstead and 2 designates an ordinary and well-known form of spring of the so-called box form resting in place on the bedstead as is usual.

For the purposes of my invention it is necessary to have a device simulating an ordinary hinge having one leaf thereof secured to the spring structure 2. In my preferred form I employ two hinges 3 and 4. Each hinge has, in effect, two leaves, one leaf 5 is attached in any suitable or appropriate manner to the box spring 2. In my preferred form, as shown in cross section in Fig. 3, the pintle of an ordinary hinge is substituted by a wire 6 which may pass around the sides and two ends of the spring and may be drawn tightly enough so as to remain in place and act as a pintle for both hinges 3 and 4. One of the leaves 5 of each hinge is preferably hidden within the interior of the spring 2, the top covering 7 of the

box spring covering the leaf 5 and being attached thereto in any suitable or appropriate manner as by sewing.

The other leaves of the springs are preferably 5 projections as 8 depending from a complete metal band 9 passing around both sides and the ends of the mattress. This metal band 9 is apertured in substantially the center of both sides and at both ends and at each of these apertures there 10 is a pin, as 10, shown in detail in Fig. 5. Each of these pivot pins has an enlarged head as at 11, a reduced shank as at 12, and passing through a through bore 13 in the band 9 is then enlarged as at 14 to form a hand grip. The collar 30 is 15 positioned on the shank 12 of the pin 10. This collar just fits within the through orifice 13 of the band 9. Between the end of the collar 30 and the shoulder 15 is the compression spring 16 which serves to keep pin 10 in the outward left 20 hand position within the mattress as shown particularly in Fig. 5. This is accomplished by slotting the shank 12 as at 31 and passing through the slot and the collar 30 the cross pin 17. This cross pin bears against the inside surfaces of 25 the band 9 as at 18 and 19, so that by grasping the hand grip 14 the pin 10 may be withdrawn against the spring 16 from the orifice in the clasp- 30 ing member 27 and the mattress 25, but the spring will normally keep the enlarged end 11 in place in the clasp- 35 ing member 27 in the mattress 25. The band 9 is formed not only with the through bore 13 but also with a through slot 20 which extends both below and above the bore 13 so that by grasping the hand grip 14 pin 10 may be rotated to bring the cross pin 17 in line with the slot 20 and then the pin 10, together with its 40 associated parts, may be withdrawn entirely.

At each end of the band 9 another through bore is formed in the band as at 21 and the extreme end of a somewhat U-shaped member 22 45 is pivoted by means of a member 23 passed through its end and through the through bore, as 21, and then headed.

The U-shaped member 22 is preferably pivoted just below the end pivots of the mattress passing 50 through the band 9, as shown in Fig. 4 and also in Fig. 2. This U-shaped member is of such dimensions that when the mattress is in place on the box spring, as shown in Fig. 1, it will lie close to and parallel to the band 9, as well shown in Fig. 1, but if the hand tab 24 is grasped and the mattress lifted on hinges 3 and 4, the U-shaped member 22, which I will call a stiff leg or elevated mattress support, may be moved into the position as shown by Fig. 4, resting on the spring

2 and will support the mattress 25 at an angle to the box spring 2, as shown in Figs. 2 and 4. When the mattress is in the position, as shown by Figs. 2 and 4, it may be readily reversed either from side to side or from end to end. In Fig. 2 the side pivot pins 10 have been withdrawn from their protrusion in the mattress and so the mattress may be turned, as shown by the arrow 26, from side to side, and then the pivot pins 10 returned to place, the stiff leg raised and the mattress returned to position as shown by Fig. 1. In Fig. 4 I have shown the end pivots 10 as being withdrawn and then the mattress 25 may be pivoted upon the side pivots 10 so as to be reversed end for end.

In order to best support the mattress when pivoting on the pins 10, I provide a strengthening means such as a resilient metal clasp member 27. One of these is positioned at each of the points where a pin enters the mattress, as clearly shown in Fig. 3, and designated 27. These mattress pin supports may be attached to the mattress by any appropriate means, but I prefer to make them of somewhat springy metal and have the ends as 28 and 29 spring over the top and bottom of the mattress and so be self-retaining in place.

It will be understood from the foregoing description that I have provided a means whereby an ordinary mattress may be manipulated by a very frail woman so as to be reversed side for side and end for end. It is further to be observed that when the mattress is in the elevated position as shown in Fig. 4 it can be very much better aired than in the flat position as shown in Fig. 1. In addition when the mattress is in the elevated position it may be used as a support for the sheets and blankets during the airing process. Sheets and blankets when thus exposed are much better aired and, furthermore, it is not necessary to drape them on chairs and over furniture and drag them along a dusty floor so that they will keep clean much longer.

It is contemplated that box springs and accompanying mattress may be equipped with my invention merely by supplying the necessary new parts. These are all such that they may be readily attached to existing springs and mattresses. One leaf of the springs 3 and 4 may be readily inserted in a slit in the covering of an existing mattress, and the wire 6 may then be passed through, as a pintle, and around the existing mattress to hold the hinges in place. The band 9, together with the stiff leg 22, may be applied to the existing mattress merely by placing four of the clamp mattress pin supports 27 on the mattress at the appropriate place so that it is possible for owners of existing box springs and mattresses to equip them with my invention.

Although I have illustrated and described the hinges 3 and 4 as having one part integral with band 9, it is to be understood that I do not mean to thereby exclude a two leaf hinge, one leaf of which is integral with 9 but attached thereto, nor do I intend to exclude the use of one hinge only at the side of the mattress.

Although I have particularly described one particular physical embodiment of my invention, nevertheless I desire to have it understood that the form selected is merely illustrative and does not exhaust the possible physical embodiments of the idea of means underlying my invention.

What I claim as new and desire to secure by Letters Patent of the United States is:

1. A device for facilitating the reversal of a

mattress, in combination: band passing around both sides and both ends of a mattress, a hinge connecting the band with a box spring; said band orificed at four places, one at one end, one at the other end, one at one side and one at the other side; pivot pins passing through the orifices in the band and into the mattress whereby the mattress may be pivoted for reversal upon each pair of oppositely lying pins; a mattress clasp member claspings the mattress at the location of each of the orifices in the band, the said clasp member formed with an orifice through which a pivot pin may pass; means to hold the band and mattress in lifted position so that it is free to turn.

2. A device for facilitating the reversal of a mattress, in combination: a mattress provided with an orifice in each of its ends and in each of its sides; a resilient clasp member attached to the mattress at each of the orifices therein, said clasp member provided with an orifice aligning with the adjacent orifice in the mattress; a metallic band encircling the sides and ends of the mattress; said metallic band provided with through orifices aligning with the orifices in the mattress; a hinge comprising two leaves, one of the leaves attached to the band; a box spring, the other leaf of the hinge being inserted within the box spring; a wire surrounding the box spring and passing through and acting as a pintle for the hinge; a somewhat U-shaped member lying parallel to the said band along a part of each end and along one side of the mattress, means pivotally connecting the free ends of the U-shaped member to the band at each end thereof whereby the mattress may be lifted pivoting on the hinges and be supported in raised position by the U-shaped member resting against the box spring; pivot pins passing through the band and through the clasp member and into the mattress at each of the orifices in the mattress; means for resiliently pressing said pins into the orifices in the mattress and means for withdrawing the pins at will from the orifices in the mattress and from the orifices in the mattress clasp member whereby, when the mattress has been elevated by turning on the hinges and while supported by the U-member, a pair of oppositely disposed pins may be withdrawn and the mattress may be reversed side for side or end for end while pivoting on the remaining pins.

3. A device for facilitating the reversal of a mattress, in combination: a mattress provided with an orifice therein; a resilient clasp member bearing against the top and the bottom of the mattress and extending over the edge thereof and formed with an orifice aligning with the orifice in the mattress; a band surrounding the mattress and provided with orifices aligning the orifices in the mattress and with a slot at each orifice in the band communicating with the orifice; pivot pins having an enlarged head at one end, a reduced shank and a hand grip at the other end passing through orifices in the band, said pivot pins each having a cross pin passing through the reduced shank; a spring between the enlarged head of the pin and the band on each of the pins whereby a pin may be withdrawn from an orifice in the mattress and a clasp member by grasping the hand grip and pulling outwardly and whereby the cross pin on a pin will pass through the said slot and, upon being rotated with the pin, will rest against the surface of the band preventing it from moving inwardly into the

orifice in the mattress whereby a pair of opposite pins may be withdrawn and the mattress pivoted on the remaining opposite pins.

4. A device for facilitating the reversal of a mattress, in combination: means for pivoting a mattress on one edge thereof whereby one side thereof may be raised; means for supporting the mattress in the raised position; and means including movable pivot pins whereby the mattress may be reversed end for end or side for side while in the raised position.

5. A device for facilitating the reversal of a mattress, in combination: means adapted for attaching the mattress to a box spring whereby it may be pivoted thereon on one edge thereof; a frame surrounding the mattress; means detachably connected to the frame and mattress whereby the mattress may be pivoted in the frame so as to be reversed end for end or side for side; and means for supporting the frame in proper position while the mattress is being reversed.

6. A device for facilitating the reversal of a mattress, in combination; a mattress; a frame surrounding the mattress on both sides and both ends; a stiff leg pivoted to the frame; hinge means attached to a box spring and to the said frame whereby the mattress and frame may be raised pivoting on the hinges and supported in elevated position by the stiff leg resting against

the box spring and pivot pins supported by the frame and passing into the mattress, one on each end and one on each side; means for resiliently pressing the pivot pins into the mattress and means for facilitating manual withdrawal of the pins from the mattress whereby the mattress may be raised, pivoting on one edge remaining supported by a stiff leg resting on the box spring and then a pair of opposite pivot pins may be withdrawn from the mattress and the mattress pivoted on the remaining pins so that it may be reversed end for end or side for side.
